UNITED STATES PATENT OFFICE.

DAVID ASHMAN, OF BALTIMORE, MARYLAND, ASSIGNOR TO EAGLE MANUFACTURING CO.

MACHINE-BRAKE.

SPECIFICATION forming part of Letters Patent No. 653,637, dated July 10, 1900.

Application filed January 25, 1900. Serial No. 2,736. (No model.)

To all whom it may concern:

Be it known that I, DAVID ASHMAN, a citizen of the United States, residing at Baltimore, in the State of Maryland, have invented 5 certain new and useful Improvements in Machine-Brakes, of which the following is a specification.

This invention relates to improvements in a brake device for machines, and is especially 10 adapted for use on sewing-machines employing fly-wheels, although it is applicable to other classes of machines.

The invention is illustrated in the accompanying drawings, in which—

15 Figure 1 is a vertical longitudinal section through the frame of a machine and illustrates the application of the invention. Fig. 2 illustrates one view of the operating-lever. Fig. 3 is an inverted plan view of the contact-brake 20 device. Fig. 4 is an elevation of part of the machine-frame and of the contact-brake device.

Referring to the drawings, the letters *a a'* 25 designate two vertical standards of the frame of the machine which support the top *b* and are connected at the bottom by a stay-rod *c*, the ends of which pass through the standards and are secured thereto by means of nuts *d*. The standard *a'* is provided with a central hole *e*, 30 through which one end of the driving-shaft *f* is passed, and a fly or driving wheel *g* is mounted on the projecting end of said shaft. A guard *h* is secured to the standard *a'* by screws or bolts *i*, and said guard takes over the said 35 wheel *g*. The guard *h* is provided with a hole opposite the end of the shaft, and a cone-pointed screw *k* is secured in said hole *j*, and the cone-point takes in a correspondingly-shaped indentation in the end of the shaft, thereby forming a cone-bearing. The opposite 40 end of the shaft is also supported in a similar cone-bearing, the cone-pointed pin *k'* being secured in the standard *a*.

The standards *a* and *a'* are each provided 45 with a hole or bearing *m m'*, and a rod *n* is supported in said bearings and is movable endwise through said bearings. The rod *n* is provided at one end with two collars *o o'*, which are suitably secured thereto, and at the opposite 50 end a sleeve *p* surrounds the rod and carries a brake-arm *p'*, which extends paral-

lel with said rod and the end of which passes through an oblong hole *q* in the frame or standard *a'*. A spiral spring *r* surrounds the rod *n* and is compressed between the sleeve *p* and the standard *a'*, and said spring serves to press against the sleeve and push it and the rod endwise away from the standard *a'*. It will be seen that the oblong hole *q* in the frame, which receives the end of the brake-arm *p'*, 60 is positioned so as to guide said arm in a horizontal plane to enable it to make contact with the rim of the fly or driving wheel *g*, and at the same time this construction prevents said arm and rod *n* from turning when the arm *p'* contacts with the revolving wheel. The end of the arm *p'* has a dovetailed recess, and a block of rubber or other material *s* is inserted in said recess and contacts with the rim of the fly-wheel when it is desired to stop the latter 70 from revolving.

The standard *a* at a point between the driving-shaft *f* and endwise-movable rod *n* is provided with a bracket *t*, which supports an operating-lever *u*. The lever *u* at one end is 75 provided with two prongs *v*, which take on opposite sides of the rod *n* between the two collars *o o'*. The said lever is provided with a pivot-hole *w* for a pivot-pin *w'*, by means of which it is pivoted to the bracket *t*, and at the 80 lower end the lever terminates in a flat plate *x*, which may be actuated by the knee of the operator.

It will be seen that the collars *o o'* and the sleeve *p* and arm *p'* are all adjustable on the 85 rod *n*.

The operation is as follows: Supposing the machine to be running and it being desired to stop the same, the operator will press against the plate *x* of the lever *u*, pushing the 90 lower end of the lever toward the standard *a*, whereupon the upper or prong end of the lever will move in the opposite direction or toward the standard *a'*. This movement of the prong end of the lever will push the rod *n* toward the standard *a'* and cause the brake-arm *p'* to project through the oblong hole *q* and press the rubber *s* against the rim of the driving-wheel *g*. The rod *n* and brake-arm *p'*, it has been stated, are prevented from 100 turning with the wheel *g* because of the walls of the oblong hole *q*.

Having thus described my invention, what I claim as new, and desire to secure by Letters Patent, is—

In a brake device for machines, the combination of the standards a , a' , formed with bearings m , m' , and one of said standards a' being also formed with a hole q separate from its bearing; a shaft supported in said standards; a drive or fly wheel carried thereon; a rod movable endwise through bearings in a direction parallel with said shaft; a sleeve surrounding and secured to the movable rod and formed with a brake-arm p' extending parallel with and spaced from said rod and

projecting through the said separate hole q in the standard in proximity to the said drive or fly wheel; a spring coiled around the movable rod in the space between the latter and said brake-arm and interposed between said sleeve and the adjacent standard, and means for moving said rod and brake-arm.

In testimony whereof I affix my signature in the presence of two witnesses.

DAVID ASHMAN.
